[57] CLAIM

The ornamental design for a facial massage instrument, substantially as shown and described.

DESCRIPTION

FIG. 1 is a top view of a facial massage instrument embodying my new design.

FIG. 2 is a side view of an instrument embodying my new design.

FIG. 3 is a bottom view of an instrument embodying my new design.

FIG. 4 is a front view of an instrument embodying my new design, and

FIG. 5 is a rear view of an instrument embodying my new design.

FIG. 6 is a top view of another embodiment of my new facial massage instrument, embodying my new design.

FIG. 7 is a side view thereof.

FIG. 8 is a bottom view thereof, and

FIGS. 9 and 10 are respectively front and rear views thereof.

Fig. 1.

Fig. 2.

Fig. 3.

Fig. 4.

Fig. 5.
